UNITED STATES PATENT OFFICE.

JACOB NETTER, OF CHICAGO, ILLINOIS, ASSIGNOR TO THEONETT & CO., OF CHICAGO, ILLINOIS, A CORPORATION OF ILLINOIS.

DESIGN FOR A BOTTLE.

Application filed February 1, 1927. Serial No. 20,568. Term of patent 14 years.

To all whom it may concern:

Be it known that I, JACOB NETTER, a citizen of the United States of America, residing at Chicago, in the county of Cook and State of Illinois, have invented a new, original, and ornamental Design for Bottles, of which the following is a specification, reference being had to the accompanying drawing, forming a part hereof.

Fig. 2 is a front elevation of the bottle.

I claim:

The ornamental design for a bottle, as shown.

JACOB NETTER.
